UNITED STATES PATENT OFFICE.

HERMANN LEMP, OF LYNN, MASSACHUSETTS, ASSIGNOR TO THE THOMSON-HOUSTON ELECTRIC COMPANY, OF CONNECTICUT.

COMPENSATING ELECTRIC METER.

SPECIFICATION forming part of Letters Patent No. 416,339, dated December 3, 1889.

Application filed September 24, 1889. Serial No. 324,970. (No model.)

To all whom it may concern:

Be it known that I, HERMANN LEMP, a citizen of the United States, and a resident of Lynn, in the county of Essex and State of Massachusetts, have invented a certain new and useful Compensating Meter, of which the following is a specification.

My invention relates to means for measuring electricity in those cases where two or more groups of translating devices, each group having translating devices connected in multiple, are themselves connected in series with one another, so as to form what is sometimes termed a "series-multiple circuit."

15 The object of my invention is to provide for the correct registration of the electric energy consumed without employing a separate measuring-instrument for each group.

My invention applies more particularly to those circuits or systems in which an intermediate wire or conductor connected between the groups of translating devices leads to an inductive transfer-coil, as in patents to E. Thomson, No. 360,125, dated March 29, 1887, and to E. W. Rice, Jr., No. 400,486, dated April 2, 1889.

My invention applies also to that system of distribution known as the "three-wire system," in which a third wire passing between two groups of translating devices leads to a point between separate dynamos supplying electric energy for the system.

35 My invention is applicable alike to those systems in which alternating electric currents are employed and to those in which continuous currents are used.

I have hereinafter shown various arrangements of apparatus whereby the invention may be carried out in connection with translating devices operated by either kind of current.

45 The invention consists, essentially, in determining the action of the meter, or operating it in accordance with the resultant magnetic or electric effect produced by currents flowing in the intermediate wire between two groups of translating devices and an outside wire or wires of the group, as will be herein-after more fully described.

50 In the case of alternating currents the re-

sultant magnetic effect may be that of two primary coils or a converter, the secondary of which supplies the current that operates the meter directly, or the resultant magnetic effect of the two coils may be used for operating the armature of a magnet, which shall determine or control the rate of operation of the meter actuated by some external magnetic power.

By my invention an indefinite number of groups of translating devices in multiple series may have their total current measured by the use of a single instrument, and without the use of a single instrument for each group, as would ordinarily be required where intermediate conductors lead from points between the groups and at some times form the path of current passing to or from the groups.

As will hereinafter more clearly appear, the compounding of the two currents, or of the effects produced by the two coils in which such currents flow, may be such that the magnetism shall be the sum of the effects of the current, or the compounding may be such that at some times the effect of one shall be subtracted from that of the other.

I shall hereinafter, for the sake of illustration, only describe my invention as applied to circuits containing electric incandescent lamps.

In the accompanying drawings, Figures 1 and 2 are diagrams illustrating arrangements embodying my invention as applied to two groups of lamps fed with alternating currents. Fig. 3 is a diagram illustrating a modification as applied to two groups, while Fig. 4 shows the extension of the primary to six groups. Fig. 5 is a table illustrating the operation of the system Fig. 4. Fig. 6 illustrates an arrangement that may be employed in cases where continuous currents are used in the translating devices. Fig. 7 illustrates another mechanism that may be used for measuring current from two or more groups of translating devices in accordance with my invention. Fig. 8 illustrates a means that may be used for alternating electric currents.

Referring to Fig. 1, M is an electric meter of any proper description for registering al-

ternating currents, and S is the secondary of a transformer or induction-coil connected to such meter. The primary P of such transformer is in two sections 1 2.

5 E is an induction transfer-coil such as described in the patents of E. Thomson and E. W. Rice, Jr., before referred to. The groups of lamps I II have the lamps of each group in multiple with one another, while the two groups are in series between the two sides A B of the system. An intermediate wire w connects the transfer-coil with the connection between the two groups. Section 1 of the primary is in series with group I, and section 15 2 in series with group II. As will be seen, the current under ordinary conditions will pass from one side of the system, as A, first through the section 1 of the primary, then through the group of lamps I, then 20 through the second group of lamps II, and thence through the section 2 of the primary to the other wire or conductor B. The two sections are wound so that they will add their effects to one another in generating current in the secondary S . It is obvious that if the balance in the two groups I II is destroyed and current pass through the conductor w to equalize the flow in the group where a change is taking place, as described 25 in the patents of Thomson and Rice before referred to, such current will be subtracted from one of the sections of the primary and the total inductive effect on the secondary will be correspondingly lessened.

30 I have shown the number of turns of the sections 1 and 2 as the same, because it is assumed that the conditions of potential between the two sides of each group are the same; but it is obvious that the wire w might 40 be connected to a point to one or the other side of the center of the induction transfer-coil, and that the number of turns of the coils would be then changed so that they would be proportional to the potential of the 45 two groups.

50 H indicates a partial winding formed as a shunt-coil across the terminals of one of the groups to provide energy when the lamps are not in use, so that the inertia of the meter 55 may be overcome. As it is supposed that the condition of potential in each group is kept constant, or practically so, it is obvious that the shunt or partial winding H may be extended over both groups—that is to say, from one side A to the other side B of the system, or from one terminal of the section 1 of the primary to the corresponding terminal of the other section 2.

60 The compound action of the primaries in setting up current for operating the meter under various conditions of the groups I II might be obtained by placing the two sections of the primary in circuit, as indicated in Fig. 2. Here, as before, each coil is in series with its corresponding group; but any difference in the number of lamps in one group or the other will be felt in the meter

through the withdrawal from one section of the compound primary of a part of the current which ordinarily flows through the same.

70 In the modification indicated in Fig. 3 one of the sections of the primary is placed in the intermediate wire or conductor w instead of in the series circuit with the group of lamps. In this instance the section 1 of the primary under normal conditions will generate the whole current which operates the meter, the section 2 being out of action. In this case if the current or energy normally consumed in each of the two groups I II be the same, section 1 will register for the whole, conductor w being without current. Section 2 is applied so as to subtract its effect from that of 1 if the number of lamps in group II, for instance, be diminished. If section 1 have 85 two turns, section 2 would have one turn. While section 1 may register for the whole number of lamps in both groups, section 2 may, when group I is out of operation entirely, register for group II. If group II is 90 out of operation entirely, the current which under normal conditions passed through such group now passes through the section 2 to the intermediate wire and opposes the action of section 1, so as to produce a compound or 95 resultant inductive effect in the secondary equivalent to one turn of primary.

100 The extension of the principle to six groups is shown in Fig. 4. Section 1 of the primary, in series with all the groups, like section 1 of Fig. 3, has six turns. Section 2, in series with five groups, but in the first intermediate wire, has five turns, and so on, the number of turns or ampère effects of the sections diminishing according to the position of the section or the 105 intermediate wire in which it is placed with relation to the series of groups until the last intermediate wire is reached, where the coil-section 6, that produces the induction for the last or a single group, when such group only 110 is in operation, has a single turn. It is not necessary that the number of turns be exactly that mentioned, all that is requisite being that (when the potential of each group is the same as that of the others) the number of 115 turns of successive sections should be in the ratio 6 5 4 3 2 1. If the potentials required be different at different groups, the ratio of turn would be correspondingly varied. Thus, for instance, in Fig. 3, which is a simple 120 case, if the potential across group II be such that double the current is consumed normally therein over what is consumed in group I, the ratio of the turns of sections $P' P^2$ would be 3 2, or, if three groups were used in 125 the system, with a normal consumption in the groups, (proceeding in the order shown in Fig. 4,) of 1 2 4, and the number of ampère-turns of sections 1 2 3 would be in the ratio 6 5 3. If groups 1 and 2 were alone operating, current 130 in section 3 would be compounded with that in 6, giving a resultant of 3, proportioned to the consumption in groups 1 and 2, which would be in such case 3.

The action of the arrangement shown in Fig. 4 under varying conditions will be readily understood from an inspection of the table, Fig. 5. The first column gives the designation 5 of the group, and the second column shows graphically the number of ampère-turns of the several sections of the primary in the series connection with each group when such group is the first of the series to take current. Succeeding columns indicate for each group the current flowing or the ampère or magnetic effects in the coils under different conditions as to number of lamps in use in each group.

15 The effect of each coil in cutting down or increasing the total effect is indicated by the signs — and +. For instance, referring to column 1, with six lamps in each group, six ampères (for the sake of simplicity) will flow 20 through the six turns in coil 1, giving a magnetizing effect of thirty-six ampère-turns. As all the groups have six lamps each, no current will flow through the following coils; 2, 3, 4, 5, and 6, and the magnetizing effect of 25 the ampère-turns, which is thirty-six, will equal or correspond, therefore, to the number of lamps actually running. In column 2, there being no lamps in first group, no current is flowing through the first coil 1. Six ampères 30 are flowing through coil 2, which has five turns, and the magnetizing effect will be thirty. As there are no lamps in the third group, the current of six ampères has to return through coil 3, which has four turns. The current, in 35 this case going in an opposite direction to that of coil 2, will be of a negative sign. I have, therefore, in coil 3 twenty-four ampère-turns negative. Group IV, containing six lamps, again six ampères will flow through 40 coil 4, containing three turns, which will give eighteen ampère-turns of positive sign. Six ampères returning again through coil 5, which has two turns, deducts from the whole twelve ampère-turns, and, finally, six ampères flowing 45 through coil 6, which has only one turn, gives six ampère-turns positive. In summing up, the total number of effective ampère-turns will be found equal to the number of lamps burning. Column 5 shows a case in 50 which an irregular number of lamps are burning in different groups. One lamp and six turns in group I give six ampère-turns. There being three lamps in second group—that is, two more than in group 1, in series 55 with it—current for two lamps of such group flows through coil 2 in the same direction, giving ten ampère-turns. Group III, having but two lamps, one less than group II, current corresponding to one lamp flows from 60 group III through coil 3 of four turns to give four ampère-turns. In group IV six lamps are in use, current for two of which comes in series from preceding group of 2, while the current for the remaining four passes through 65 coil 4 in a direction to give twelve ampère-turns positive. Section V having but five lamps in use, current corresponding to one of

the six in preceding section passes in a direction through coil 5 to give —2, while section VI, having one less lamp than V, gives by 70 coil 6 one turn negative. Total twenty-one corresponding to whole number of lamps in use.

In Fig. 6 I have shown an organization that may be employed for carrying out my invention in connection with continuous or direct 75 currents. S is a solenoid having the two windings *a b* connected, as before described, and arranged to produce a compound magnetic field for the core C of such solenoid. The position of the core under the influence 80 of such compound field-induction, when the solenoid is supplied with a simple retractor, will obviously be dependent upon the resultant effect of the two windings *a b*. The position of the core may determine the rate of 85 registry on a meter R by moving an inclined plate having an inclined face C², which determines the amount of movement that can be produced upon the initial wheel of the register by an oscillating impulse-pawl made as a 90 friction-pawl, or otherwise constructed, oscillations of such mechanism being produced by an electro-magnet M or other mechanism periodically actuated. In the case of a magnet M the local battery L B, or a shunt taken 95 from main supply-circuit, and a circuit-breaker actuated by a train of wheels and placed in the circuit of the battery and magnet produce the desired action.

Fig. 7 illustrates another mechanism that 100 may be employed in the same manner. Pendulum C⁵ carries the actuating device for the register, and its rate of vibration is determined by the resultant magnetic field produced by the two coils *a b*. The pendulum 105 carries an armature moving in the magnetic field.

Fig. 8 shows another organization that may be used in the case of alternating electric currents. The two coils *a b* are herein connected 110 to the intermediate wire of the translating devices and to the outside wire o, as before explained, so that their effects will tend to oppose one another. The resultant magnetic field produced by such coils is employed as 115 the field for an armature C⁶, adapted to rotate by the action of an alternating field, with a speed dependent upon the strength of such field. To produce rotation of such armature any of the expedients employed with alternating-current motors may be used—as, for instance, an auxiliary field applied to the armature and producing, in conjunction with the combined field of *a b*, two alternating fields whose phases are displaced, as explained in the patent to Thomson and Wightman, No. 399,801, dated March 19, 1889. The armature of the motor may be geared directly 120 to the meter-train, so that the movement of the meter will depend upon the speed of rotation of the armature.

What I claim as my invention is—

1. The combination, with a series of groups of translating devices having intermediate

wires or connections, as described, of a series of electric coils, the ampère-turns of which are in ratio depending upon the turns of the coils in the series of groups, and an electric 5 meter operated by electric energy which is the resultant of the combined action of such coils, as and for the purpose described.

2. The combination of a series of groups of translating devices, an electric meter common 10 to the same, and a series of magnet-coils carrying the controlling or energizing current which directly or indirectly governs the action of the meter, one of such coils being in the series circuit with all the groups of translating 15 devices, while the remainder are disposed in intermediate wires or connections leading to the groups and are of decreasing effect proportionately to their position in the series and to the normal consumption of the 20 energy in the several groups, as and for the purpose described.

3. The combination, with a series of two or more groups of translating devices having an intermediate wire or conductor, as described, 25 of an electric meter in a secondary electric circuit and two or more primaries common to such secondary circuit and connected severally with the groups of translating devices, as and for the purpose described.

30 4. The combination, with a series of groups of translating devices, of an electric meter in a secondary circuit and a series of primaries common to such secondary circuit, one of such series being in the series circuit with all

the groups, while the remainder are disposed 35 in intermediate wire or connections leading to the groups and are of decreasing effect proportionately to their position in the series and to the normal consumption of energy in the several groups, as and for the purpose de- 40 scribed.

5. The herein-described method of obtaining a registry or measurement of electric current supplied to a series of groups of translating devices, consisting in compounding the 45 current flowing in a series connection with the groups and in an intermediate wire or connection, as described, and actuating or controlling the meter by the resultant effect, as and for the purpose set forth.

50 6. The herein-described method of obtaining a registry or measurement of electric current supplied to a series of groups of translating devices having an intermediate wire or wires, as described, under variations of load 55 in such groups, consisting in opposing the action of the current in a series connection with two or more groups by the action of current in an intermediate wire or wires of such groups.

Signed at Lynn, in the county of Essex and State of Massachusetts, this 14th day of September, A. D. 1889.

HIERMANN LEMP.
